MOTOR MECHANISM

Julius J. Thaisz, Rutherford, N. J.

Application September 26, 1938, Serial No. 231,808

3 Claims. (Cl. 123—56)

This invention relates to motor mechanism. More particularly it belongs in the class of gasoline motors customarily termed two-cycle motors, and has for its object the production of a motor 5 of special construction which is believed to possess unusual simplicity of design of the entire assembly, and very economical to build. The parts are readily assembled and easily and cheaply manufactured. The special construction of this 10 invention is thought to eliminate valves, timing gears or chains, and cam shafts, while it has force feed lubrication, and can use an ordinary carburetor. The number of moving parts in the complete assembly is at a minimum.

15 In the accompanying drawings are illustrated the construction and disposition of the various parts, and Fig. 1 represents a top plan view of all the parts assembled.

Fig. 2 is a longitudinal vertical section through 20 two oppositely arranged cylinders and the crank case.

Fig. 3 is a longitudinal section of one of the cylinders.

Fig. 4 is a sectional view taken on broken line 25 4—4 of Fig. 3.

Fig. 5 is a sectional view taken on the broken line 5—5 of Fig. 3.

Fig. 6 is a vertical sectional view showing the oil pump structure on the crank shaft.

30 Throughout the drawings and description the same number is used to refer to the same part.

In the drawings, Fig. 1, the cylinders 1, 2, 3 and 4 are shown axially and oppositely arranged, with the transverse crank shaft 5 crossing the

35 crank case 6. Covering the top of the crank case is a hood 7 which will be again mentioned.

As shown in Fig. 1 an oil pump 8, is mounted upon the crank shaft and driven by a pulley 9 on the shaft. Into the top of the pump is led a

40 tube or pipe connection 10 which is in open communication with the bottom pan or cover 11 illustrated in Fig. 2. Oil collects in the bottom pan 11 and is drawn therefrom by the pump and discharged through tubular outlet 12 into a dis-

45 tributing oil pipe 13. This invention is not limited to the size or form of the tubular conduits. From pipe 13 a pipe 14 leads to the top or hood 7 of the crank case, and connects with a discharge tube 15 extending downwardly as shown in Fig. 2. Oil

50 collects in the crank case through orifices 16, and in the bottom pan through like openings 17. From the oil pipe 13 oil is delivered by way of tubes 18, 19, 20 and 21 to the location of the cylinders, and each cylinder has a tube 22 in communication with the interior of the cylinder, as

set out in Fig. 2. It will be understood that the pipe connection 10 shown in the Fig. 1 extends downwardly and is connected with the bottom portion of the pan 11 which is shown in Fig. 2, so that the oil may be drawn by the pump 8 from the lowest part of the mechanism into which it has dripped through the openings 17 illustrated in Fig. 2.

Further considering Fig. 1, pulleys 23 and 24 drive water pumps such as pump 25, and by way 10 of conduits 26 cooling water is delivered into the water chambers 26 with which each cylinder is provided. Conduits similar to 26, not shown, may be located in connection with the lower portions of the cylinders, in order that the cooling water 15 may be circulated by the pumps 25 and like. The invention is not limited to any particular construction of water pump or the necessary connections. Pulleys 23 and 24 are belted to oil pump 20 pulley 9.

In Fig. 1 are shown the external exhaust pipes 27 and 28, and inlet connections 29 and 30, and in Fig. 2 are illustrated the piston 31 with rod 32 at the right, and the companion piston 33 with rod 34 at the left. The crank slide 35 moves up 25 and down in a crank slide guide 36, the arrangement being sometimes termed a Scotch yoke.

As best shown in Fig. 2 each cylinder has the exhaust ports 37 and inlet ports 38 arranged adjacently on the same side of the cylinder, and it 30 will be noted that the tube injecting the lubricant into the cylinder is inserted between the intake and exhaust ports as shown. This is held by applicant to be a simple and convenient arrangement, and is regarded as one of the points 35 of improvement in this invention. No other or specific entrance for the lubricating tube is necessary.

As best shown in Fig. 3, the cylinder is further provided with the ports 39 and 40 connected by 40 the by-pass 41.

Considering Fig. 6, it will be noted that the oil pump 8, driven by pulley 9, is provided with an eccentric 42, which operates a spring returned plunger 43, and the entrance of the oil is controlled by a ball valve 44. Applicant holds that the construction of the oil pump may be variously modified without departing from the scope of this invention.

In operation, starting when the charge has just 50 exploded and when the piston is at the inner end of its stroke as shown at the left in Fig. 2, gas is entering through the intake ports due to the partial vacuum created by the instroke of the piston, as the cylinder is closed by the stuffing 55

box of the crank case. Upon the opposite movement of the piston the intake ports are closed and the gas that has entered the cylinder is compressed by the movement of the piston. The gas is also compressed in the by-pass 41. When the piston has moved all the way, the compressed gas travels into the cylinder through the ports 39. It is deflected by the fin or ridge on the head of the piston in an upward direction and turns down against the cylinder wall and forces the exhaust gases out by way of the exhaust ports 37. On the return stroke of the piston the gas is finally compressed and fired as the piston reaches the termination of its stroke. The operation repeats itself. At the same time, the oil pump and its connections lubricates the interior of the cylinder and discharges oil upon the crank shaft and its connections in the crank case as herein described.

I claim:

20. 1. A motor having the construction comprising a crank shaft, cylinders oppositely arranged, a crank case between the cylinders, a crank slide and crank slide guide within the crank case, said cylinders having piston rods connected with the said guide, an oil pump mounted upon the said crank shaft and constructed to be operated thereby, oil tubes communicating with the interiors of the cylinders and with the said pump, and an oil tube extending through the top of the 25 crank case for discharging oil upon the crank slide and guide within the case and communicating with the said pump.

2. A motor having the construction comprising a crank shaft, cylinders oppositely arranged, the said cylinders having cooling water chambers, a crank case between the cylinders, a crank slide and crank slide guide within the crank case, said 5 cylinders having piston rods connected with the said guide, an oil pump mounted upon the said crank shaft and constructed to be operated thereby, oil tubes communicating with the interiors of the cylinders and with the said pump, an oil tube 10 passing through the top of the crank case for discharging oil upon the crank slide and guide within the case and communicating with the said pump, and pumps arranged to be operated by the said crank shaft and having connections with 15 the said cooling water chambers of the cylinders.

3. A motor having the construction comprising a plurality of cylinders oppositely arranged, a crank case between the cylinders, a transverse shaft passing through the crank case, a crank 20 upon the shaft, said cylinders having pistons operatively connected with the crank, the wall of each of said cylinders having on the same side inlet and outlet ports formed in the wall of the cylinder adjacently, and the wall of the cylinder 25 having a lubricating oil inlet formed in the wall between the said inlet and outlet ports, an oil pump constructed and arranged to be operated by the said shaft, and tubular connections extending from said lubricating oil inlet to the oil 30 pump.

JULIUS J. THAISZ.
